Primary Examiner — Marianne N Pandozzi

(57) **CLAIM**

The ornamental design for a beverage dispenser.

DESCRIPTION

FIG. 1 is a front perspective view of a beverage dispenser showing our new design;

FIG. 2 is a rear perspective view thereof;

FIG. 3 is a top plan view thereof;

FIG. 4 is a bottom plan view thereof;

FIG. 5 is a right side view thereof;

FIG. 6 is a left side view thereof;

FIG. 7 is a front view thereof; and,

FIG. 8 is a rear view thereof.

The broken lines in the drawing depict environmental subject matter only and form no part of the claimed design.
